US00D964396S

(12) **United States Design Patent** (10) Patent No.: **US D964,396 S**
Crawford et al. (45) Date of Patent: **** Sep. 20, 2022**

(54) **DISPLAY SCREEN OR PORTION THEREOF WITH GRAPHICAL USER INTERFACE**

(71) Applicant: **Apple Inc.**, Cupertino, CA (US)

(72) Inventors: **Jared Andrew Crawford**, Apex, NC (US); **Christian Xavier Dalonzo**, San Francisco, CA (US); **Robert Garcia, III**, San Francisco, CA (US)

(73) Assignee: **Apple Inc.**, Cupertino, CA (US)

(**) Term: **15 Years**

(21) Appl. No.: **29/829,694**

(22) Filed: **Mar. 7, 2022**

Related U.S. Application Data

(63) Continuation of application No. 29/738,902, filed on Jun. 20, 2020, now Pat. No. Des. 947,866.

CLAIM

(57) The ornamental design for a display screen or portion thereof with graphical user interface, as shown and described.

DESCRIPTION

The patent or application file contains at least one drawing executed in color. Copies of this patent or patent application publication with color drawing(s) will be provided by the Office upon request and payment of the necessary fee. The FIGURE is a front view of a display screen or portion thereof with graphical user interface showing the claimed design.

The outer broken lines in the FIGURE show a display screen or portion thereof, and form no part of the claimed design. The other broken lines in the FIGURE show portions of the graphical user interface that form no part of the claimed design.
